Camoriano and Associates(57) CLAIM

The ornamental design for a buoyant beverage holder, as shown and described.

DESCRIPTION

FIG. 1 is a front view of a buoyant beverage holder showing my new design;

FIG. 2 is a top view thereof;

FIG. 3 is a bottom view thereof;

FIG. 4 is a top perspective view thereof; and,

FIG. 5 is a bottom perspective view thereof.

The broken lines are for illustrative purposes only and form no part of the claimed design.
